DICTATING MACHINE

Eliot F. Noyes, New Canaan, Conn., assignor to International Business Machines Corporation, Armonk, N.Y., a corporation of New York

Filed Dec. 29, 1964, Ser. No. 83,199

Term of patent 14 years

(Cl. D26—14)

FIG. 1

FIG. 2

FIG. 3

FIG. 4

FIG. 5

FIG. 6

FIG. 1 is a left side, front and bottom perspective view of a dictating machine, showing my new design;

FIG. 2 is a top plan view, to a reduced scale;

FIG. 3 is a left side elevational view, to a reduced scale;

FIG. 4 is a front elevational view, to a reduced scale;

FIG. 5 is a right side elevational view, to a reduced scale;

FIG. 6 is a bottom plan view thereof, to a reduced scale.

The characteristic features of my design reside in the portions shown in solid lines.

I claim:

The ornamental design for a dictating machine, substantially as shown and described.
